(57) **CLAIM**

The ornamental design for a fishing pole lamp, as shown and described.

DESCRIPTION

FIG. 1 is a front elevational view of a fishing pole lamp showing my new design, an electrical cord being shown in broken lines for illustrative purposes only and forms no part of the design;

FIG. 2 is a rear, elevational view thereof;

FIG. 3 is a left, elevational view thereof;

FIG. 4 is a right, elevational view thereof;

FIG. 5 is a top view thereof;

FIG. 6 is a bottom view thereof; and

FIG. 7 is a front, perspective view thereof; and,

FIG. 8 is a front perspective view of another embodiment of a fishing pole lamp of the invention, this embodiment having a different base shape and a lure rather than a bobber as fishing tackle with the fishing line, the other views being otherwise similar to those shown in FIGS. 1-6.
